UNITED STATES PATENT OFFICE.

WILLIAM R. NICOLL, OF OWATONNA, MINNESOTA, ASSIGNOR TO DAVIS WATKINS
DAIRYMEN'S MANUFACTURING COMPANY, A CORPORATION OF DELAWARE.

BUTTER-PRINTER.

1,268,600.

Specification of Letters Patent. Patented June 4, 1918.

Application filed January 29, 1916. Serial No. 74,991.

To all whom it may concern:

Be it known that I, WILLIAM R. NICOLL, a citizen of the United States, residing at Owatonna, in the county of Steele and State 5 of Minnesota, have invented certain new and useful Improvements in Butter-Printers, of which the following is a specification.

This invention relates to a device for 10 printing or stamping butter or the like and for dividing a mass of butter into certain predetermined smaller masses or quantities which are of convenient form and size for handling, selling and the like. The principal object of the invention is to provide a 15 new and improved construction, combination and arrangement of parts for accomplishing the desired results.

In the accompanying drawings, Figure 1 20 is a top plan view showing parts in section of a device constructed in accordance with the principles of my invention; Fig. 2 is a longitudinal sectional view of the same, and Fig. 3 is a cross sectional view.

Briefly stated, the operation of the present device consists in filling a fixed frame 25 which has a movable bottom with a quantity of butter and then pressing the butter through the frame against suitably spaced dividers which separate the mass of butter into a predetermined number of smaller bodies having a definite size and shape.

In carrying out this invention a pair of end members 5, preferably of metal, are 30 rigidly connected by a pair of base members 6, usually of wood, and spaced apart at the center to allow for the action and movement of certain operative parts. Each end member is formed with perforated guide 40 lugs 7 at the bottom and with a slot 8 in one or both of which is pivoted a lever 9 with an operating arm 10 extending beyond the outer end of the member in which it is attached. The slot 8 is continued toward the 45 top of each member 5, and in this portion of the slot a locking member 11 is pivoted which has a winged fastening nut 12. At the base of each member it is formed with shoulders 13 and 14 by means of which 50 other parts of the printer are supported.

A frame 15 for containing butter and open at the bottom and top is of a size to be supported by the shoulders 14. Movable through this frame is a plate 16 provided 55 with guide posts 17 which extend through

the perforated lugs 7 of the end members 5 and guide the plate in its movement through the frame 15. This plate normally rests on the shoulders 13 at the bottom of the frame 15 and may be apertured or solid, as desired. 60 It is preferably provided with countersunk portions 18 on its upper face in which are seated a plurality of smaller plates or pads 19. These pads are freely removable from the plate and are spaced slightly apart by 65 the countersunk portions.

At the top of the butter-containing frame 15 is a dividing frame 20 which preferably extends around the outside of the frame 15 and is seated on the cross-pieces 21 of the 70 end members 5. This dividing frame 20 has slots 22 at the ends in which the fastening members 11 are movable so that the winged nuts 12 engage the upper side of the dividing frame. Extending across the dividing 75 frame and across the top of the butter containing frame 15 at predetermined distances, are a plurality of dividers each comprising a wire 23 fixed at one side of the dividing frame 20 by a fastening device 24 80 and removably attached at the other side of the dividing frame by means of a threaded screw 25 which is rotated to tighten or disengage the wire 23 from its side. The dividers 23 are so disposed that when the plate 85 16 is raised they will be seated in the space between the pads 19 so that the top surface of the pads in their raised position will be above the wires 23, as clearly shown in dotted outline in Fig. 2.

The operating means for the plate 16 comprises the handled operating lever 9 and a lever 26 pivoted in the base members 6 and connected to the other lever 9 by means of a link 27. These levers are not connected to the plate 16 but merely engage the bottom of the plate moving it upwardly as desired, the plate and levers falling of their own weight.

In operation, frames 15 filled with butter 100 may be placed on the end members 5 and locked in position or the empty frames may be placed on the end members and then filled with butter. The dividing frame 20 is placed over the frame 15 and the plate 16 105 with its pads 19 is moved upwardly pressing the butter in the frame against the dividing members and therefore cutting the butter into as many blocks as desired, and each block is then removed on its pad 19 so that 110

there is no necessity whatever for the hands of an operator actually coming in contact with the butter. The blocks thus formed may be wrapped after first removing the 5 pads 19 therefrom and the pads returned to the plate 16 for further use. These pads 19 may be provided with any suitable design or inscription by forming raised portions or depressions thereon which will appear on 10 the divided blocks of butter the reverse of the design on the pad. In this way the blocks of butter may be marked with a trade mark or any suitable name or the like.

It is obvious that any number of blocks, 15 or blocks of any size, or of different sizes may be made with this device by simply varying the number of dividers for the positions of the dividers. It is further obvious that blocks less in depth than the full depth 20 of the frame 15 may be produced by raising the plate 16 only part way by means of the lever arm 10 and holding it in such position, whereupon the mass of butter protruding above the top of the frame 15 may then be 25 removed or cut off by running a cutter along the top of the frame 15. This method might be employed, for example in cutting pats of butter for hotel use and the like.

It is obvious that other modifications in 30 the structure of the device might be made without departing from the spirit and scope of the invention.

What I claim is:

1. A butter printer comprising a fixed 35 frame open at top and bottom, a bottom plate movable therein, and a plurality of supporting levers unconnected thereto, one of which has a handle for manually moving the plate through the frame.
2. A butter printer comprising an open fixed frame for containing a known quantity of butter, a plate forming a bottom for the frame, a plurality of connected levers for supporting the plate at the ends thereof and 45 for moving both ends thereof uniformly through the frame when one lever is actuated, and guiding means comprising a fixed support and posts slideable therein and fixed to the plate.
3. In a butter printer, the combination with a supporting base, of end pieces spaced apart thereon, a frame supported by and securable to the end pieces, a plate movable through the frame, guiding means for said 55 plate extending through said end pieces, and a dividing frame removably attached at the top of the other frame.
4. In a butter printer, the combination with a pair of rigidly connected end pieces, 60 a frame supported at the corners by said

end pieces, releasable means for securing the frame to the end pieces, a plate movable through the frame in such fixed position, the end pieces having guide openings, and guide posts secured to the plate extending through 65 said openings to direct the plate in its movement through the frame.

5. In a butter printer, the combination with end members rigidly connected and spaced apart, a frame for confining butter 70 loosely supported thereon, pivoted fastening means in connection with each member for holding the said frame in position, a plate forming a bottom movable through the frame for discharging butter therefrom, and means for operating the plate comprising a pair of connected levers upon which the plate normally rests one of which is pivoted in each of said end members with an arm extending therefrom for manually operating 75 both levers.

6. In a butter printer, the combination with a pair of end members, of a base rigidly secured to the members for spacing them apart, a frame supported by the members, a dividing frame adjacent the upper side of the other frame with dividers extending across it, means for detachably connecting the two frames to the end members, a plate movable through the first mentioned 85 frame for discharging butter from it, a plurality of removable pads supported by the plate, and means for moving the plate through the said frame comprising a pair of levers one of which is provided with an operating arm both pivoted below the plate supporting and engaging it but not connected thereto.

7. In a butter printer, the combination with a fixed frame for containing butter and dividing means in connection therewith, a plate movable through the frame for discharging butter therefrom and dividing it into a predetermined number of smaller quantities, a pair of connected levers for 100 moving the plate and a separate removable pad loosely supported by the plate for each of the divided portions of the butter whereby the said divided portions may each be separately removed from the printer with 105 its pad.

In testimony whereof I have signed my name to this specification, in the presence of two subscribing witnesses; on this 25th day of January A. D. 1916.

WILLIAM R. NICOLL
